Primary Examiner — Cynthia R Underwood

(57) CLAIM

The ornamental design for a tablet case, as shown and described.

DESCRIPTION

FIG. 1 is a perspective view of a tablet case showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another perspective view thereof where a kickstand is in an open state;

FIG. 10 is an enlarged view of portion 10 in FIG. 1 thereof; and,

FIG. 11 is an enlarged view of portion 11 in FIG. 2 thereof. The broken lines in the drawings are for the purpose of illustrating portions of the tablet case, which form no part of the claimed design.
